[57] CLAIM

The ornamental design for a ladder paint bucket hook, as shown and described.

DESCRIPTION

FIG. 1 is a perspective view of a ladder paint bucket hook showing my new design;

FIG. 2 is an enlarged left side elevational view thereof, the opposite side being a mirror image;

FIG. 3 is a top plan view thereof;

FIG. 4 is a bottom plan view thereof;

FIG. 5 is a front elevational view thereof; and,

FIG. 6 is a rear elevational view.

The broken line showing of a ladder and paint bucket are illustrative purposes only and forms no part of the claimed design.
